Primary Examiner — George D. Kirschbaum*Assistant Examiner* — Kendra Leslie Hamilton(74) *Attorney, Agent, or Firm* — Suzanne Kikel, Patent Agent(57) **CLAIM**

The ornamental design for a garment for canines, as shown and described.

DESCRIPTION

FIG. 1 is a front top right perspective view of a garment for canines, showing my new design in a condition of use.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a bottom view thereof; and,

FIG. 7 is a top view thereof.

In FIG. 1, the broken line showing of a dog depicts environmental subject matter only and forms no part of the claimed design.

The drawings are shaded to indicate contrasting surfaces.
